Primary Examiner — Vy N Koenig*Assistant Examiner* — Kimberly Barnes(74) *Attorney, Agent, or Firm* — Fitzpatrick, Cella, Harper & Scinto(57) **CLAIM**

The ornamental design for a shingle, as shown and described.

DESCRIPTION

FIG. 1 is a top plan view of our design for a shingle.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a perspective view thereof.

FIG. 7 is a bottom plan view thereof.

FIG. 8 is a top plan view of a second embodiment of our design for a shingle.

FIG. 9 is a front elevation view thereof.

FIG. 10 is a left side elevation view thereof.

FIG. 11 is a right side elevation view thereof.

FIG. 12 is a perspective view thereof; and,

FIG. 13 is a bottom plan view thereof.
